(57) **CLAIM**

The ornamental design for a camera lens attachment for a tablet or mobile device, as shown and described.

DESCRIPTION

FIG. 1 is a perspective view of an embodiment of our new design for a camera lens attachment for a tablet or mobile device;

FIG. 2 is a 2nd perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a perspective view of a second embodiment of our new design for a camera lens attachment for a tablet or mobile device;

FIG. 10 is a 2nd perspective view thereof;

FIG. 11 is a front view thereof;

FIG. 12 is a back view thereof;

FIG. 13 is a left view thereof;

FIG. 14 is a right view thereof;

FIG. 15 is a top view thereof; and,

FIG. 16 is a bottom view thereof.

In the drawings, the broken lines show portions of a camera lens attachment that form no part of the claimed design.
